US00D991052S

(12) **United States Design Patent** (10) **Patent No.:** **US D991,052 S**
Bonorand et al. (45) **Date of Patent:** **** Jul. 4, 2023**

(54) **CLOCK**

(71) Applicant: **ProductiveNetwork GmbH**, Winterthur (CH)

(72) Inventors: **Cristoffel Bonorand**, Zurich (CH);
Adrian Reto Hauser, Winterthur (CH)

(73) Assignee: **ProductiveNetwork GmbH**, Winterthur (CH)

(**) Term: **15 Years**

(21) Appl. No.: **29/772,830**

(22) Filed: **Mar. 4, 2021**

Related U.S. Application Data

(63) Continuation of application No. 35/508,231, filed on Jun. 27, 2019 (U.S. filing date under 35 U.S.C. 384), and having an international filing date of Jun. 27, 2019, now abandoned.

(57) **CLAIM**

The ornamental design for a clock, as shown and described.

DESCRIPTION

FIG. 1 is a front perspective view of the clock that we consider to be our invention;

FIG. 2 is a back perspective view;

FIG. 3 is a front perspective view of a second embodiment;

FIG. 4 is a back perspective view;

FIG. 5 is a front perspective view of a third embodiment;

FIG. 6 is a back perspective view;

FIG. 7 is a front perspective view of a fourth embodiment;

FIG. 8 is a back perspective view;

FIG. 9 is a front perspective view of a fifth embodiment; and,

FIG. 10 is a back perspective view.

The black shading in the figures represents a contrasting color.

The broken line showing is included for the purpose of illustrating portions of the "article" and forms no part of the claimed design.

1 Claim, 10 Drawing Sheets
